FIG. 2. Robert Burnside, Inventor

By Mariont Marion
Attorneys

UNITED STATES PATENT OFFICE.

ROBERT BURNSIDE, OF MONTREAL, CANADA.

PACKING-CUP.

SPECIFICATION forming part of Letters Patent No. 758,410, dated April 26, 1904.

Application filed December 16, 1903. Serial No. 185,347. (No model.)

To all whom it may concern.

Be it known that I, ROBERT BURNSIDE, a subject of the King of Great Britain, residing at Montreal, county of Hochelaga, Province of Quebec, Canada, have invented certain new and useful Improvements in Packing-Cups; and I do hereby declare that the following is a full, clear, and exact description of the invention, such as will enable others skilled in the art to 10 which it appertains to make and use the same.

My invention relates to stuffing-boxes or vibration-boxes for steam-cylinders, and especially to the construction of such parts when used in connection with locomotive-cylinders.

15 In applying stuffing-boxes to locomotive-cylinders, and especially in renewing the packing-rings, a difficulty arises due to the presence of a collar upon the piston near the cross-head, which collar prevents the passing of 20 rings which should retain the packing.

The object of this invention is to provide a stuffing-box or vibration-box especially adapted to overcome the difficulty mentioned, but at the same time efficient and durable in construction.

The invention consists in the construction and combination of parts to be more fully described hereinafter and definitely set forth in the claims.

30 In the drawings, which fully illustrate my invention, Figure 1 is a longitudinal section through the stuffing-box or vibration-box constructed according to my invention. In this view the piston-rod is shown, together with a portion of its cross-head end. Fig. 2 is a front elevation of the box, the piston-rod being shown in section. Fig. 3 is a perspective representing a half of the base-ring which is instrumental in retaining the packing-rings. Fig. 4 is a perspective representing a half of a follower-ring which is also instrumental in retaining the packing-rings. Fig. 5 is a perspective of a yoke-ring used in conjunction with two half-rings such as shown 45 in Fig. 4.

Throughout the drawings and specification the same numerals of reference denote like parts.

Referring more particularly to the parts, 150 1 represents a portion of a cylinder-head, which

is provided with a bore 2, through which the piston-rod 3 passes, the said bore 2 having an enlarged counterbore 3^a, forming a recess which receives a powerful helical spring 4, as shown, the purpose of which spring will appear more fully hereinafter. Upon the outer face of the head a gland 5 is attached, the same having bolt-openings 6 for this purpose. This gland is provided with a bore 7, which terminates in a spherically-bored shoulder 8, 55 which constitutes a seat for a main ring 9, as shown. This main ring has a bore 10 sufficiently large to pass over the collar 11, which is formed upon the rod 3, near the outer extremity thereof. This ring may also have an 60 enlarged counterbore 12, as indicated. The inner face of this main ring constitutes a seat for a vibration-cup 13, which cup is preferably of substantially cylindrical form and has a conical bore 14, terminating in a plain cylindrical bore 15, beyond which there is formed an inwardly-projecting shoulder or flange 16, at which point the bore is substantially of the same diameter as the bore 10 and adapted, like the bore 10, to enable the vibration-cup to be placed over the aforesaid collar 11. 70

The inner face of the shoulder 16 constitutes a seat for a base-ring 17, which ring is preferably formed of two half-rings 18, one 80 of which is very clearly shown in Fig. 3. These half-rings have cylindrical outer faces 19, adapted to be received by the bore 15, and have conically-bored faces 20, as shown, which latter faces constitute a seat for a main packing-ring 21, which is also formed in halves, like the ring 17. The inner diameter of the ring 17 is slightly larger than the diameter of the piston-rod 3, as shown, while the bore through the ring 21 is adapted to fit the lateral surface of the piston-rod accurately. 85

Behind the main packing-ring 21 other packing-rings 22 23 are received, the same being preferably of the cross-section shown and made in halves, like the ring 21. 90

The packing-rings are retained by a follower-ring 24, which is made in halves 25, one of which is very clearly shown in Fig. 4. This ring comprises a body 26, having on its inner face a laterally-projecting flange 27, 95 100

which flange is of sufficiently large diameter so that its edges will project beyond the edges of the counterbore 3^a in the cylinder-head. The halves of this ring 24 are held in position 5 by a yoke-ring 28, the same consisting of a plain ring, as shown clearly in Fig. 5. This ring passes over the body 26 and rests upon the under face of the flange 27, as indicated most clearly in Fig. 1.

10 The parts contained in the gland having been assembled in the manner described and as illustrated, these parts would then be applied to the outer face of the cylinder-head, as illustrated in Fig. 1, so that the spring 4 could 15 thrust against the follower-ring 24, and in order to insure perfect steam-tightness of the gland at its inner face the same is bolted down upon a packing-wire 29, which is preferably formed of soft copper or similar material.

20 The ease with which the vibration-box described could be applied to the cylinder-head should readily appear, it being understood that the gland 5, the main ring 9, and the vibration-cup are all of sufficiently large diameter 25 to pass over the collar 11. The base-ring 15 being split, it will be readily put in position after the other parts have been passed beyond the collar. In like manner the packing-rings could be applied and the follower-ring 30 24, which is held in place by the yoke-ring 28, which is of large diameter, as illustrated. In this manner the difficulty arising from the presence of the collar is overcome simply and a vibration-box is produced which 35 is simple in construction and admirably adapted for its purpose. The spring 4 operates to maintain the packing-rings in position within the vibration-cup, and the fact that the follower-ring 24 is of greater diameter than the 40 bore 3^a prevents any possibility of the said follower passing back into the bore 3^a when the piston is moving inwardly, as it might tend to do by reason of the friction developed. This is an advantageous feature, as it 45 prevents any possibility of the packing becoming loose or deranged from this cause.

While I have shown in the accompanying drawings the preferred form of my invention, it will be understood that I do not limit myself 50 to the precise form shown, for many of the details may be changed in form or position without affecting the operativeness or utility of my invention, and I therefore reserve the

right to make all such modifications as are included within the scope of the following claims 55 or of mechanical equivalents to the structures set forth.

Having described my invention, what I claim, and desire to secure by Letters Patent, is—

1. In combination, a gland adapted to be attached to a cylinder-head and adapted to have a piston-rod pass therethrough, a vibration-cup, means for supporting the same within said gland, said vibration-cup having an enlarged diameter with a forwardly-projecting shoulder, a base-ring formed in sections and of a restricted inner diameter seating upon said shoulder, packing-rings seating upon said base-ring within said cup, and a follower-ring 70 adapted to retain said packing-rings.

2. In combination, a gland adapted to be attached to the outer side of a cylinder-head and adapted to have a piston-rod pass therethrough, a vibration-cup supported therein 75 and having an enlarged inner diameter with an inwardly-projecting shoulder, a base-ring formed in sections and having a restricted diameter seating upon said shoulder, packing-rings seating upon said base-ring, a follower-ring made in sections and adapted to retain 80 said packing-rings, and a yoke-ring of enlarged diameter encircling the sections of said follower-ring.

3. In combination, a gland, a piston-rod 85 passing therethrough and having a collar of enlarged diameter, a vibration-cup carried within said gland and having an enlarged inner diameter adapted to pass over said collar and having an inwardly-projecting shoulder, 90 a base-ring formed in sections seating upon said shoulder and having a restricted inner diameter, packing-rings seating upon said base-ring, a follower-ring made in sections and having a restricted diameter, and a laterally-projecting flange, a yoke-ring encircling the body of said follower-ring, a cylinder-head having a counterbored recess therein, and a spring received within said recess and thrusting against said follower-ring.

In witness whereof I have hereunto set my hand in the presence of two witnesses.

ROBERT BURNSIDE.
